No. 14,828 FEB 26, 1884

UNITED STATES PATENT OFFICE.

SARAH JANE SHIELS, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 14,828, dated February 26, 1884.

Application filed January 23, 1884. Term of patent 3½ years.

To all whom it may concern:

Be it known that I, SARAH JANE SHIELS, of the city, county, and State of New York, have invented and produced a new and original Design for a Pattern of a Lady's Costume, (numbered 9,024;) and I do hereby declare that the engraved prints accompanying this specification convey to any one accustomed to using paper patterns a clear understanding of how a garment made up by the pattern will appear.

The design shows a closely-fitted body-back that is widened and lengthened to form the back of the walking-skirt, and displays under-folded plaits at the lower ends of its seams; a closely-fitted basque-front, with added side

skirt portions; a deep left-front drapery exhibiting clustered plaits in its front edge, and overlapped at the top by a deep plain right-side drapery, flaring widely at its front edge 20 and overlapping a triangular panel; coat-sleeves, a lapel-collar, and a standing collar.

What I claim as my invention, and desire to secure by Letters Patent, is—

The design for a lady's costume, as shown in the engraved prints accompanying this specification.

SARAH JANE SHIELS.
